**ELECTRICAL MUSICAL INSTRUMENT
KEYING CIRCUITRY**

Donald M. Park, Raleigh, N.C., assignor to Park-Baker
Electronic Development Corporation, Raleigh, N.C., a
corporation of North Carolina

Filed Dec. 12, 1963, Ser. No. 330,147
12 Claims. (Cl. 84—1.11)

This invention relates generally to electric musical instruments and, more particularly, to keying circuits for electric musical instruments.

Most modern electronic organs include a plurality of tone generators, usually in the form of oscillators, which are coupled to an audio system through appropriate valves or gates. These valves, which are commonly referred to as "keying" circuits, are controlled by the keys of the organ keyboard so that operation of the keys determines which tones are transmitted through the valves to the audio system. In general, it can be said that the tone signals from the tone generators are fed into the valves along "controlling" paths, and that the selected signals are transmitted from the valves to the audio system along "controlled" paths.

It is the main object of the present invention to provide an improved keying circuit for electronic organs.

It is another object of the invention to provide an improved keying circuit which provides at least two controlled paths for each controlling path.

It is a further object to provide such a circuit which is considerably more economical than the keying circuits proposed heretofore.

A still further object is to provide such a circuit which converts tone signals in the form of sawtooth or sine waves to substantially square waves.

Still another object is to provide such a circuit which provides tone sustaining on each controlled path.

Another object is to provide such a circuit which permits the addition of tremolo on each controlled path.

A further object is to provide such a circuit which permits the use of very economical oscillators.

Other aims and advantages of the invention will be apparent from the following description and appended claims.

In the drawings:

FIGURE 1 is a general block diagram showing a portion of one particular electronic organ system embodying the present invention;

FIGURE 2 is a schematic circuit diagram of one specific embodiment of the system of FIGURE 1; and

FIGURE 3 is an illustration of the wave shapes of the tone signals at various points throughout the circuit of FIGURE 2.

In accordance with the present invention, there is provided an electric musical instrument having a plurality of tone-generating oscillators; a plurality of electronic valves each of which has at least two controlling paths for receiving tone signals from the oscillators, and at least four voltage responsive controlled paths for selectively transmitting the tone signals, each controlling path being operatively associated with two of the controlled paths and being operatively connected to one of the oscillators; tone-modifying means operatively connected to the controlled paths and an audio system operatively connected to the tone-modifying means; a source of voltage for actuating the controlled paths; and key-operated switching means for applying the voltage to the voltage responsive controlled paths so as to selectively actuate the controlled paths to transmit selected tone signals to the respective tone-modifying circuits connected to the selectively actuated controlled paths.

A preferred embodiment of the present invention will now be described in more detail by referring to the drawings.

Referring first to the general block diagram in FIGURE 1, there is illustrated a portion of an electronic organ system which generally comprises a master tone-generating oscillator 10; three slave tone-generating oscillators 12, 14, and 16 which follow the master oscillator 10; two electronic valve 19 and 20 which provide two controlled paths 21 and 22 for each controlling path 23 from the tone-generating oscillators 10, 12, 14, and 16; a key-operated switch 24 operatively connecting each of the controlled paths 21 and 22 to tone-modifying circuits 25 and 26, respectively; and an audio system comprising an amplifier 28 and a speaker 30. Although the illustrated portion of the organ system includes only four tone-generating oscillators and two electronic valves, it will be understood that all these elements would be multiplied many times in the complete organ system and, therefore, the advantages of this invention would also be multiplied many times.

To briefly explain the operation of the system shown in FIGURE 1, the master oscillator 10 generates a first tone signal which is fed along a first controlling path 23a to the first electronic valve 19. The signal from the master oscillator 10 is also fed into the first slave oscillator 12, which produces a second tone signal at half the frequency of the first tone signal. This second tone signal is fed along a second controlling path 23b to the first electronic valve 19, and is also fed into the second slave oscillator 14. The slave oscillator 14 generates a third tone signal at half the frequency of the second tone signal and feeds it into the third slave oscillator 16 and also along a controlling path 23c to the second electronic valve 20. And, finally, the slave oscillator 16 generates a fourth tone signal at half the frequency of the third tone signal and feeds it along a controlling path 23d to the second valve 20.

The electronic valves 19 and 20 provide two controlled paths 21 and 22 for each controlling path 23, and the opening of the valves to the various controlled paths 21 and 22 is controlled by the key-operated switches 24 located in each of the paths 21 and 22. For example, if the key-operated switch 24a is closed, the valve 19 opens to transmit the first tone signal from controlling path 23a along the controlled path 21a to the tone-modifying circuit 25. Similarly, if the key-operated switch 24d is closed, the valve 19 opens to transmit the second tone signal from controlling path 23b along controlled path 22b to the tone-modifying circuit 26. From the tone-modifying circuits, the signals are transmitted on through the amplifier 28 and the speaker 30 of the audio system.

Since the electronic valves 19 and 20 provide two controlled paths for each controlling path, they permit two different audio effects to be obtained from each tone signal. In other words, the organ keys can be operated to pass each of the basic tone signals through either or both of the two tone-modifying circuits 25 and 26. Thus, although the illustrated system produces signals of only four different frequencies, i.e. four different notes, the multiple controlled paths provided by the valves 19 and 20 permit the production of eight different audio effects, or two different effects for each note.

One specific embodiment of the general system of FIGURE 1 is illustrated in FIGURE 2. The master oscillator 10, which is a conventional transistorized Hartley oscillator, generates a first tone signal at a predetermined constant frequency which represents the highest note to be produced by the organ. For example, a suitable frequency for this first tone signal in most organs is about 2,000 cycles per second. This first tone signal, which is in the form of a sine wave, is passed through a load re-

sistor 50 into the first electronic valve 19, and also into the first slave tone-generating oscillator 12.

An integral part of each of the valves 19 and 20 is a triode 52 having dual grids 55a and 55b and four plates 54, 56, 58, and 60, such as a 12FQ8. The first tone signal from the oscillator 10 is applied to the grid 55a of the triode, while each of the four plates is connected to a bias voltage $-V$ through a load resistor 70 and a bias resistor 68. Each of the plate circuits of the triode 52 is also connected to a tone-modifying circuit 25 or 26 through a coupling capacitor 72, and to a B+ voltage through a switch 24 which is manually operated by a key on the organ keyboard.

Operatively associated with each of the key-operated switches 24 is a tone-sustaining circuit 76 comprising a resistor 78 and a capacitor 80 connected in parallel with each other. The resistor 78 of each of the circuits 76 is connected to ground through a switch 82 which is controlled by a manually operated rocker arm (not shown). The tone-sustaining circuit 76 is operative only when the switch 82 is closed.

The tone-modifying circuits 25 and 26 may be any of the standard circuits commonly employed in electric musical systems to modify the particular audio effect of any given note. Typical examples of such circuits are the various filters, such as flute filters and string filters, and tone-selecting amplifiers.

The three slave tone-generating oscillators 12, 14, and 16 are all conventional relaxation oscillators composed of a neon tube 84 in parallel with a capacitor 86 and connected to a voltage V through a resistor 88. The output of each of the slave oscillators is fed to a grid 55 of one of the triodes 52 through a resistance-capacitance network comprising a capacitor 90, a resistor 91, and a resistor 92. The output of the slave oscillator 12 is also fed through a coupling circuit composed of a capacitor 94 and a diode 95 to the slave oscillator 14 which, in turn, feeds its output through a similar coupling circuit to the slave oscillator 16. The outputs of the slave oscillators 14 and 16 are also fed to grids 55a and 55b, respectively, of the second valve circuit 20.

OPERATION OF THE SYSTEM OF FIGURE 2

In operation, the master oscillator 10 generates a first constant-frequency tone signal which is applied to both the valve 19 and the first slave oscillator 12 in the form of a sine wave. Each of the slave oscillators operates as a conventional relaxation oscillator, i.e., the capacitor 86 charges up until it fires the neon tube, then discharges and charges up again, thereby generating a continuous tone signal in the form of a sawtooth wave. The value of the capacitor 86 in each of the slave oscillators is chosen to produce an output signal at exactly half the frequency of the input signal from the preceding oscillator. In other words, the master oscillator 10 produces a first tone signal at a frequency f , the first slave oscillator 12 produces a second tone signal at a frequency $f/2$, the second slave oscillator 14 produces a third tone signal at a frequency $f/4$, and the third slave oscillator 16 produces a fourth tone signal at a frequency $f/8$. In each case, the slave oscillator is locked at the desired frequency by the input signal from the preceding oscillator. Although any desired number of oscillators may be employed, it will be understood that the tone signals generated by the oscillators are all even multiples or submultiples of each other.

As the output signal of each of the slave oscillators 12 and 14 is fed to the succeeding slave oscillator, the signal is passed through a coupling circuit composed of a capacitor 94 and a diode 95, which shape the tone signal wave to a form suitable for locking the next oscillator at the desired frequency. The operation of the coupling circuit can be best explained by referring to the wave forms shown in FIGURE 3. Referring first to the slave oscillator 12, the output signal of this oscillator at point

A in FIGURE 2 appears as wave A in FIGURE 3. Wave A is a standard sawtooth wave at some predetermined positive voltage V. As the sawtooth wave A passes through the capacitor 94, it appears as wave B at point B in FIGURE 2, which serves to lock oscillator 14 at half the frequency of oscillator 12. The output of the oscillator 14 at point C in FIGURE 2 appears as wave C in FIGURE 3. Wave C has the same sawtooth shape as wave A, but at half the frequency.

Returning now to point A in the first oscillator 12, the output signal at this point is passed through a voltage-dividing, wave-shaping network comprising the capacitor 90 and resistors 91 and 92. The signal is first clamped, as indicated by wave D appearing at point D in FIGURE 2, and then clipped, as indicated by wave E appearing at point E in FIGURE 2. From point E, the signal is applied to the grid 55b of the first valve 19. One important feature of this invention is that the output signal from the electronic valves 19 and 20 are square waves, which generally produce a very desirable tone quality in an electronic organ. In order to obtain these square waves, it is important that the capacitor 90 and the resistors 91 and 92 be adjusted to produce a wave E which, when applied to the grid 55b, causes a substantially square wave to be produced at the plates 58 and 60. In other words, the voltage applied to the grid 55b must extend into both the saturation region and the cutoff region of the tube 52. The output signal of the tube 52 then appears as wave F at points F in the plate circuits.

As can be seen from the foregoing description, the various tone signals from the master oscillator 10 and the slave oscillators 12, 14, and 16 are applied continuously to the respective grids 55 of the tubes 52, thereby providing a controlling path for each pair of controlled paths represented by the two plates associated with each grid. Of course, the various plate circuits are normally non-conducting because of the bias voltage $-V$ applied across the resistors 68 and 70. But each time one of the manually operated key switches 24 is closed, the particular plate associated with that switch conducts the tone signal associated with that plate through a coupling capacitor 72 to one of the tone-modifying circuits 25 or 26, and then on through the audio system. As can be seen in FIGURE 2, one of the controlled paths associated with each controlling path leads to the tone modifying circuit 25, while the other controlled path associated with each controlling path leads to the other tone-modifying circuit 25. Thus, by selectively operating the keys 24, the organ player can not only select different notes or tone signals, but also can select different audio effects or voices for each note. For example, the tone signal that is fed into the valve 19 from the master oscillator 10 can be transmitted through either tone-modifying circuit 25 or 26, depending on whether key 24a or 24b is depressed, and the same is true of each of the three other tone signals that are fed into the valves from the three servant oscillators.

When it is desired to sustain the tone signals being conducted along any of the controlled paths from the valves 19 and 20, the appropriate switches 82 are closed so as to render the appropriate RC tone-sustaining circuits 76 operative. Of course, the values of the resistors 78 and the capacitors 80 in these circuits may be adjusted to provide any desired sustaining period.

One important feature of the circuit of FIGURE 2 is that tremolo can be added to any of the tone signals by simply modulating the B+ voltage which is applied to the plates upon closing of the key-operated switches 24. Thus, it is possible to add tremolo to each of the controlled paths.

Another significant feature of the circuit of this invention is that it stabilizes the tone-generating oscillators by providing a relatively high load impedance, thereby permitting the use of very economical oscillators, such as the neon-tube relaxation oscillators employed in the circuit of FIGURE 2.

While various specific forms of the present invention have been illustrated and described herein in some detail, it will be apparent that the same are susceptible of numerous modifications within the scope of the invention. For example, although the invention has been described with particular reference to a system of tone generators comprising a master oscillator generating a sine wave and a plurality of slave oscillators generating sawtooth wave, it will be understood that the keying circuit of the invention may be used with numerous other tone generators producing various other wave shapes. Similarly, instead of using a master-slave tone-generating system, each tone-generating oscillator could be free running and precisely tuned to the exact desired frequency. Moreover, although the electronic valve and the controlling and controlled paths provided thereby have been described with particular reference to vacuum tubes, such as the 12FQ8, it can be seen that the same general circuit can be made with other active electronic devices, such as by the use of transistors having two bases and four collectors.

What is claimed is.

1. In an electric musical instrument having a plurality of tone-generating oscillators:

- (a) a plurality of electronic valves, each of which has at least two controlling paths and at least four voltage responsive controlled paths, each controlling path being operatively associated with two of said controlled paths and being operatively connected to one of said oscillators;
- (b) a voltage source; and
- (c) manually operated percussive switching means for operatively connecting said voltage source to selected controlled paths, thereby transmitting selected tone signals from said controlling paths through said valves and along said selected controlled paths.

2. The electric musical instrument of claim 1 which includes resistance-capacitance tone-sustaining means and a second manually operated switching means for operatively connecting said tone-sustaining means to said controlled paths.

3. The electric musical instrument of claim 1 wherein the voltage level of said voltage source is sufficiently high to cause said electronic valves to conduct a tone signal from a controlling path to the selected controlled path.

4. The electric musical instrument of claim 1 which includes tone-modifying means operatively connected to each of said controlled paths.

5. The electric musical instrument of claim 1 wherein a different tone-modifying means is operatively connected to each of the two controlled paths operatively associated with each controlling path.

6. An electric musical instrument comprising:

- (a) a plurality of tone-generating oscillators including a master Hartley oscillator and a sequence of slave relaxation oscillators operatively connected to said master oscillator;
- (b) a plurality of triodes each of which has a dual grid and four plates, each of said grids being operatively connected to one of said tone-generating oscillators, thereby providing at least two plates operatively associated with each oscillator;
- (c) tone modifying circuits operatively connected to

said plates, a different tone-modifying circuit being operatively connected to each of the plates associated with a single oscillator;

- (d) an audio system including an amplifier and a speaker operatively connected to said tone-modifying circuits; and
- (e) a D.-C. voltage source and manually operative percussive switching means for operatively connecting said voltage source to selected plates of said triodes, thereby transmitting selected tone signals from said grids through the selected plates, through the tone-modifying circuits operatively connected to the selected plates, and through said audio system.

7. The electric musical instrument of claim 6 wherein the tone signals applied to said grids extend into both the saturation regions and the cutoff regions of said triodes, thereby causing a substantially square wave to be transmitted by said triodes regardless of the wave shape of the signals applied to said grids.

8. The electric musical instrument of claim 6 wherein the tone signal from each of said oscillators is fed to said grid through a resistance-capacitance network which shapes and clamps said signal such that it extends into both the saturation region and the cutoff region of said triode, thereby causing a substantially square wave to be transmitted through the plates of said triodes.

9. The electric musical instrument of claim 6 which includes means for modulating said D.-C. voltage.

10. In an electric musical instrument having a plurality of tone-generating oscillators:

- (a) a plurality of electronic valves, each of which has at least one controlling path for receiving tone signals from said oscillators and at least four voltage responsive controlled paths for selectively transmitting said paths for selectively transmitting said tone signals, each controlling path being operatively connected to one of said oscillators;
- (b) tone-modifying circuits operatively connected to said controlled paths and an audio system operatively connected to said tone-modifying circuits;
- (c) a source of voltage for actuating said controlled paths; and
- (d) key-operated switching means for applying said voltage to said voltage responsive controlled paths so as to selectively actuate said controlled paths to transmit selected tone signals to the respective tone-modifying circuits connected to the selectively actuated controlled paths.

11. The electric musical instrument of claim 10 which includes resistance-capacitance tone-sustaining means and manually operated switching means for operatively connecting said tone-sustaining means to said controlled paths.

12. The electric musical instrument of claim 10 wherein each of said controlling paths includes a resistance-capacitance network which shapes and clamps the tone signal such that said valve transmits a substantially square wave to said controlled paths.
